UNITED STATES PATENT OFFICE.

FELIX OSTROUT DE CARIE, OF SACRAMENTO, CALIFORNIA.

POWER-OPERATED DOOR.

Application filed May 5, 1924. Serial No. 711,177.

To all whom it may concern:

Be it known that I, FELIX OSTROUT DE CARIE, a citizen of the United States, residing at Sacramento, in the county of Sacramento and State of California, have invented a new and useful Power-Operated Door, of which the following is a specification.

The present invention relates to power operated doors especially designed for use in connection with incinerators, ash pits, railway car bottoms or the like, the primary object of the invention being to provide novel means for operating the doors from a point remote from the doors.

Another important object of the invention is to provide means for operating the doors under heavy weights that could not be operated manually.

Another important object of the invention is to provide movable door sections operated on trackways, the trackways being of such constructions as to cause the doors to move upwardly to their active positions when they have reached a predetermined position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a longitudinal sectional view through a device constructed in accordance with the invention.

Figure 2 is a longitudinal sectional view through a door operating mechanism wherein only one door section is employed, the door section being shown in its active position.

Figure 3 is a sectional view taken on line 3-3 of Figure 1.

Figure 4 is a sectional view taken on line 4-4 of Figure 1.

Figure 5 is a plan view disclosing a modified form of the invention.

Figure 6 is a side elevational view of a still further modified form of the invention disclosing a door in its active position.

Figure 7 is a side elevational view of the

operating device as shown by Figure 6, the door being in its open position.

Referring to the drawings in detail, the reference character 5 designates the bottom of an incinerator, ash pit or the like, which is formed with the usual discharge opening 6 through which material may be removed.

The opening is supplied with a rectangular frame 7 which has an inclined wall 8 adapted to cooperate with the inclined flange 9 formed integral with the door sections 10, the door sections being formed preferably of metal and constructed to closely fit within the frame.

Supported directly under the opening are I-beams 11 which not only act as braces for the bottom 5, but provide trackways for the carriages, to be hereinafter more fully described, the lower inner flanges of the I-beams being shown as supporting the rollers 12 which are tapered to properly fit the inclinations of the flanges.

Each of the carriages includes a base 13 formed with suitable openings to accommodate the shafts 14 on which the wheels 12 are positioned there being provided links 15 connected with the shafts in such a way as to swing with respect thereto to accomplish the opening and closing of the door sections.

Depending from the under surface of each door section are spaced apertured ears 16 between which the links 15 operate, there being provided suitable pivot pins 17 for connecting the links to the ears.

Extending inwardly from the I-beams 11 are flanges 18 that have upwardly curved ends lying in proximity to the openings 6, the flanges being of such widths as to extend into the path of travel of the closure sections 10 as they are moved from their closing position, with the result that as the carriages 13 are moved, the closures will follow the flanges 18 resulting in the closures being moved from their open to their closed positions or vice versa, according to the direction of travel of the carriages 13.

Associated with the carriages, and disposed adjacent to the ends of the I-beams, are cylinders 19 mounted on the arms 20 that are secured to the under surface of the bottom 5. Operating within the cylinders 19 are pistons 21 that have connection with the piston rods 22, the forward ends of which are secured to the carriages 13, 110

so that movement of the pistons within the cylinders will result in a relative movement of the carriages to operate the closures.

Pipes 23 extend into the cylinders at points 5 adjacent to the ends thereof, so that by a suitable valve mechanism not shown, fluid may be directed to the cylinders at points between the piston and head of the cylinders to move the pistons within their cylinders 10 in a well known manner.

In the form of the invention as illustrated by Figure 2 of the drawings, a single door is illustrated as operated by a power device, the door being indicated by the reference character 24 and shown as connected with the carriage 25 by means of the connecting links 26 in such a way that the door 24 may move vertically with respect to the carriage 25.

20 The carriage operates on the lower sections of the I-beams 27 supported under the floor 28 and are of lengths to permit the door 24 to move to a position in spaced relation with the opening closed by the door. It is to be 25 understood that two of these I-beams are employed and arranged in spaced relation with each other on opposite sides of the door 24, providing trackways for the rollers 29 that support the carriage 25.

30 Connected with the carriage 25 is an operating rod 30 carrying a piston 31 at one end, which piston moves in the cylinder 32. Suitable pipes 33 establish communication between the cylinder 32 and a source of liquid 35 supply so that by controlling a suitable valve not shown, fluid may be forced into the ends of the cylinder to cause the operation of the rod.

In Figure 5, the cylinder is indicated at 40 34 in which the pistons 35 operate, the pistons being designed to control the opening and closing of the closures 36 from a point laterally thereof.

Connected with the pistons 35 are the rods 45 37 that have connection with the rods 38 shown as extending inwardly and connected with the central portions of the closures 36. In this form of the invention, fluid enters 50 the cylinder through the pipe 39 which results in the pistons being moved away from each other, resulting in a relative movement of the closures 36 connected therewith. The pistons are returned by causing fluid to enter 55 the cylinder through the pipes 40 disposed at the ends thereof.

As shown by Figures 6 and 7 of the drawings, a modified form of closure is shown and includes rollers 41 that support the inclined closure 42 adapted to close the dis-

charge end of the hopper 43 secured under the flooring 44 in a manner to receive the contents or material supported on the floor.

Spaced I-beams 45 provide the trackway for the rollers and are supported in a suitable manner under the floor 44. Disposed at 60 on end of the I-beam 45 is a cylinder 46 in which operates a piston mounted on one end of the piston rod 47 that has its forward end connected with the closure 42 at 48.

From the foregoing it will be obvious that 70 due to the construction as shown and described, relatively large closures supporting heavy weight may be readily and easily operated by merely manipulating a suitable valve.

75 It is believed that in view of the foregoing detail description, a further detail description as to the operation of the device is unnecessary.

I claim:

1. In a device of the character described, a floor having an opening, a trackway under the opening, a carriage adapted to move longitudinally of the trackway, pivoted link members mounted on the carriage, a door having pivotal connection with the upper ends of the link members, means for moving the carriage, and said door adapted to move upwardly to close the opening in the floor.

2. In a device of the character described, a floor having an opening, a trackway positioned under the opening, a wall at the end of the trackway, a carriage adapted to move on the trackway, link members mounted on the carriage, a closure pivotally connected with the upper ends of the link members, said closure adapted to swing downwardly onto the carriage, the forward end of the closure adapted to normally lie in advance of the carriage to engage the wall, and means for moving the carriage forwardly to elevate the closure.

3. In a device of the character described, a floor having an opening, a trackway disposed under the opening, a carriage movable longitudinally of the trackway, link members pivotally connected with the carriage, a closure pivotally connected with the upper ends of the link members, a flange providing a track and having upwardly extended ends disposed within the opening, said closure adapted to ride on the last mentioned track, and means for moving the carriage forwardly to move the closure into the opening.

In testimony that I claim the foregoing 115 as my own, I have hereto affixed my signature.

FELIX OSTROUT DE CARIE.
